TO ACKERMAN-BLAESSER-FEZZEY, INC., OF DETROIT, MICHIGAN, A CORPORATION OF
MICHIGAN

CLUTCH MECHANISM

Application filed July 28, 1930. Serial No. 471,375.

This invention relates to clutch mechanism and the object of the invention is to provide a clutch mechanism for use with a gear driven window regulator whereby the drive gear is locked from movement in either direction upon release of the crank for turning the gear.

Another object of the invention is to provide clutch means for locking the drive gear from turning in either direction and arranged so that the clutches are released by rotation of the crank in either direction.

A further object of the invention is to provide a driving gear for a window regulator adapted to be so held that there is no possibility of movement of the driving gear, thus eliminating back lash of the window regulator mechanism when going over rough roads.

A further object of the invention is to provide a double clutch mechanism, one of which is adapted to be released by primary rotation of the crank and the other of which is adapted to be released upon rotation of the drive gear by rotation of the crank.

These objects and the several novel features of the invention are hereinafter more fully described and claimed and the preferred form of construction by which these objects are attained is shown in the accompanying drawings in which—

Fig. 1 is an elevation of the door of a closed automobile body showing the window regulator in dotted lines.

Fig. 2 is an enlarged longitudinal section through the drive gear and clutch mechanism.

Fig. 3 is a side elevation of the drive gear.

Fig. 4 is an end view thereof.

Fig. 5 is a section taken on line 5—5 of Fig. 2 and showing the parts in their proper relation by dotted lines.

Fig. 6 is a similar section taken on line 6—6 of Fig. 2.

Fig. 7 is a sectional perspective of the end of the drive shaft.

In the usual window regulator construction, a plate 1, shown in Figs. 1, 2 and 6 is usually provided on which the regulator is

mounted. As shown in Fig. 2, the plate 1 is provided with an aperture to receive the lower half 2 of the housing for the clutch mechanism. The upper half 3 of this housing is provided with a flange 4 and rivets 5 extend through the two halves of the housing and through the supporting plate 1 as shown. The flange 4, as shown in Fig. 5, is provided with a raised portion 6 through which the edge of one of the gears of the regulator may extend into mesh with the drive gear. The drive gear 7 is provided with a hub 8 on one side thereof and with a hub 9 on the opposite side thereof, both hubs being formed integrally with the said gear.

The hubs 8 and 9 are provided with a central opening therethrough, as shown in Fig. 4, and this opening is shaped to form shoulders 10, 11, 12 and 13 extending longitudinally of the axis of the gear. As will be noted from Fig. 3, the hub 9 is provided with a slot 14, while the hub 8 is provided with a similar slot 15. A notch 16, shown in Figs. 3 and 4, is cut into the end of the hub 9 diametrically opposite the slot 14 and a similar notch 17 is cut into the hub 8 diametrically opposite the slot 15. The gear 7, as shown in these figures, is provided with an integral back plate 37, as shown in Figs. 2, 3 and 4, which extends over the edge of the teeth of the window regulator gear which meshes with the gear 7 and prevents the two gears from coming out of mesh. A coiled spring 18 is provided about the gear hub 9 and normally expands into frictional engagement with the inner wall of the housing 3, as shown in Fig. 2, and this spring 18 is provided with an inturned end 19, shown in Fig. 5, which extends into the slot 14 in the gear hub 9, as shown in dotted lines in Fig. 2. The opposite end 20 of the spring 18 extends into the notch 16 in the gear hub 9 as shown in Fig. 5. The shaft 21 for the device is shown more particularly in Fig. 2 and is provided with an end 22 to which a crank may be attached for rotating the shaft.

The portion of the shaft within the housings 2 and 3 is formed to provide a member 23, shown in Figs. 5 and 6, having a shoulder 24 adapted to engage the shoulder 13 in the

gear hub and at the opposite end is formed to provide a shoulder 25 adapted to engage the shoulder 10 of the gear hub and this member is also provided with a face 26 extending longitudinally of the shaft as shown in Figs. 6 and 7. The shaft 21 is also formed to provide a member 27 which is similar to the member 23 and is provided with a shoulder 28 adapted to engage the shoulder 12 of the gear hub and a shoulder 29 is formed thereon adapted to engage against the shoulder 11 of the gear hub and this member 27 is also provided with a face 30 extending longitudinally of the shaft, as shown in Figs. 6 and 7. A second coiled spring 31 is provided, as shown in Figs. 2 and 6, and normally expands into frictional engagement with the inner face of the housing 2 and extends about the gear hub 8. This coiled spring 31 is provided with an inturned end 32 engaging in the slot 15 of the gear hub 8 and the opposite end 33 thereof is inturned into the notch 17 of the gear hub 8. In the position shown in Fig. 5 both springs 18 and 31 are expanded into engagement with the respective housing walls which holds the springs stationary and the ends 19 and 32 of the springs 18 and 31 by their engagement in the slots 14 and 15 of the gear hubs prevents rotation of the gear and holds it stationary.

This will be understood more particularly from Fig. 5 from which it will be seen that counter-clockwise rotation of the gear 7 will press downwardly on the end 19 of the spring 18 tending to further expand the said spring into tighter engagement with the housing wall and thus prevent rotative movement of the said gear in this direction. Rotative movement of the gear 7 in a clockwise direction tends to press upwardly on the end 32 of the spring 31 thus tending to further expand the spring 31 into tighter engagement with the housing wall and prevent rotative movement of the said gear in a clockwise direction. By this arrangement, the gear 7 is held firmly from movement in a counter-clockwise or clockwise direction by any gear meshing therewith and in order to operate the device these springs must be released from engagement with the housing wall before the gear can be turned.

The release of these springs is accomplished by means of the members 23 and 27 on the crank shaft 21. Should this shaft be turned in a clockwise direction, in Fig. 5, the face 26 of the member 23 is moved into engagement with the end 33 of the spring 31 and movement of this member and shaft in a clockwise direction will move the end of the spring therewith thus contracting the spring 31 out of frictional engagement with the housing wall to release it.

Before the face 26 is moved into engagement with the end 20 of the spring 18, the shoulder 29 on the member 27 engages the

shoulder 11 in the gear hub and the shoulder 28 on the member 27 engages the shoulder 12 in the gear hub and provides a positive contact for driving the gear hubs and gear. As these shoulders come into contact by movement of the shaft 21 in a clockwise direction the gear hub is turned in a clockwise direction tending to carry the end 19 of the spring 18 therewith and tending to contract the spring 19 slightly to allow the gear to turn with the shaft.

Upon counter-clockwise rotation of the shaft 21, the face 30 thereof engages the end 20 of the spring 18 and tends to contract this spring to release it from the housing wall. As this releasing movement is continued, the shoulder 25 of the member 23 engages the shoulder 10 of the gear hub and the shoulder 24 of the member 23 engages against the shoulder 13 of the gear hub before the face 30 has moved into contact with the end 33 of the spring 31. This provides a positive drive for the gear 7 in a counter-clockwise direction and tends to pick up the end 32 of the spring 31 to contract the said spring and allow the gear 7 to rotate with the crank shaft 21. Upon release of the crank both springs expand into normal contact with the housing and lock the gear 7 from rotation in either direction.

By this arrangement the drive gear 7 is firmly held to prevent backlash of the window regulator mechanism when traveling over rough roads. The spring 18 has more surface contact with the housing due to its greater number of coils as this spring prevents downward thrust of the window and the spring 31 has fewer coils as it prevents upward thrust of the window.

From the foregoing description it becomes evident that the device is very simple and efficient in operation, will not easily get out of order, is composed of few parts and is of consequent low manufacturing cost and provides a device which accomplishes the objects described.

Having thus fully described our invention, its utility and mode of operation, what we claim and desire to secure by Letters Patent of the United States is—

1. In a clutch mechanism, a housing, a drive gear rotatable therein and provided with hub portions extending each side thereof, the said hub portions being provided with a central bore therethrough and having radial shoulders therein, a coiled spring on each side of the gear positioned about the hub, each spring normally expanding into frictional engagement with the inner wall of the housing, each hub being provided with a slot and each spring being provided with an inturned end engaging in the respective slot, the free end of each spring being also provided with an inturned end and each hub being provided with an elongated notch to

receive the said free inturned ends, a shaft rotatable within said central bore and provided with shoulders adapted to engage the shoulders of the gear hubs to limit rotative movement of the shaft in relation to the gear, the said shaft being provided with longitudinal faces adapted upon turning of the shaft to engage the ends of the springs extending into the notches of the hubs, the arrangement being such that the springs are released from frictional engagement with the housing upon engagement of the free inturned end by one of the longitudinal faces of the shaft.

2. In a clutch mechanism, a housing, a pair of coiled springs positioned in the housing in frictional engagement with the inner wall of the housing, a gear positioned in the housing and having hub portions on opposite sides provided with a central aperture therethrough, the central aperture of the gear being provided with radial driving faces extending longitudinally of the aperture, a shaft mounted in said aperture and having longitudinal driving faces adapted for engagement with the driving faces in the aperture, the shaft being mounted for limited rotative movement in relation to the gear and the springs being anchored at one end to the gear, the shaft being provided with a longitudinal groove in the surface thereof and the free ends of the coiled springs extending into the groove, the arrangement being such that primary rotative movement of the shaft in relation to the gear releases one of the springs from engagement with the housing and continued rotative movement thereof moves the driving faces of the shaft into engagement with the driving faces of the gear.

3. In a clutch mechanism, a housing, a pair of coiled springs positioned in the housing in frictional engagement with the inner wall of the housing, a gear positioned in the housing and provided with a central aperture, the gear being formed to provide radial driving faces in the central aperture, a shaft mounted in the aperture of the gear and having radial driving faces adapted to be moved into engagement with the driving faces of the gear, the shaft being mounted for limited rotative movement in relation to the gear and each spring being anchored at one end to the gear, the shaft being provided with a longitudinal groove in the surface thereof and the free end of each coiled spring extending into the groove, the arrangement being such that primary rotative movement of the shaft in relation to the gear releases one of the springs from engagement with the housing and continued rotative movement thereof moves the driving faces of the shaft into engagement with the driving faces of the gear and rotation of the gear by the shaft releases the other spring.

4. In a clutch mechanism, a housing, a gear rotatable therein and having a central aperture, a shaft mounted in the said aperture and having a series of radial driving faces extending longitudinally of the shaft, the gear being provided with companion driving faces adapted to be engaged by the driving faces of the shaft when the shaft is turned in relation to the gear, a pair of springs frictionally engaging the inner wall of the housing, the springs being anchored at one end to said gear, the shaft being provided with a longitudinal groove and the free ends of the springs being inturned into the said groove, the arrangement being such that rotation of the shaft in either direction in relation to the gear first contracts one of the springs and then moves the driving faces of the shaft into engagement with the driving faces of the gear.

5. In a clutch mechanism, a housing, a gear rotatable therein and provided with hub portions on opposite sides thereof, said hub portions being provided with a bore therethrough and having radial shoulders formed in the bore, a clutch spring anchored to each hub and normally expanding into frictional engagement with the housing wall, a shaft extending through the bore of the hub and provided with shoulders adapted to engage the shoulders of the bore to limit rotative movement of the shaft relative to the gear, the shaft being provided with longitudinal faces and the springs being provided with inturned ends adapted to be engaged by said longitudinal faces to contract the springs upon rotation of the shaft.

6. In a clutch mechanism, a housing, a pair of coiled springs positioned in the housing in frictional engagement with the wall of the housing, a gear positioned in the housing, each spring being anchored at one end to the gear, a shaft extending through the gear and adapted for limited rotative movement relative to the gear, the shaft being provided with a groove into which the free end of each spring extends, the arrangement being such that rotation of the shaft in one direction in relation to the gear contracts one of the springs and rotation of the shaft in the opposite direction in relation to the gear contracts the other of said springs.

7. In a clutch mechanism, a housing, a gear rotatable therein and having an opening therethrough, the inner face of the opening being shaped to provide a plurality of driving faces, a shaft extending through the opening and having a plurality of companion driving faces adapted to be moved into engagement with the driving faces of the gear, the shaft being adapted for limited rotation in relation to the gear, and a pair of coiled springs anchored to the gear and normally expanding into frictional engagement with the housing, and means on the shaft for releasing the

spring clutches by rotation of the shaft in either direction in relation to the gear.

8. In a clutch mechanism, a housing, a gear rotatable therein, a shaft extending through the gear, the gear and shaft being provided with companion driving faces arranged to allow limited relative rotative movement between the shaft and gear, a spring normally expanding into frictional engagement with the housing for holding the gear from rotation in the housing in one direction, a second spring normally expanding into frictional engagement with the housing for holding the gear from rotation in the housing in the opposite direction, and means on the shaft for releasing either spring upon rotation of the shaft in either direction in relation to the gear, either spring when released allowing the driving faces of the shaft to engage the driving faces of the gear.

9. In a clutch mechanism, a housing, a gear rotatable therein and having an opening therethrough, a shaft extending through the opening and adapted for limited rotative movement in relation to the gear, a pair of coiled springs anchored to the gear and normally expanding into frictional engagement with the inner wall of the housing, the shaft being provided with a pair of spaced radial faces and the free ends of the springs extending between said faces, the arrangement being such that rotation of the shaft in either direction releases the springs from frictional engagement with the housing.

- 35 10. In a clutch mechanism, a stationary housing, a gear rotatable therein and provided with hubs on opposite sides, said hubs and gear having an opening therethrough provided with a plurality of driving faces, a shaft extending through the opening and having a plurality of companion driving faces thereon, the shaft being turnable relative to the gear, and a pair of spring clutches between the hubs and housing adapted to be respectively released by rotation of the shaft in either direction.

In testimony whereof we sign this specification.

EDWARD L. ACKERMAN.
